UNITED STATES PATENT OFFICE.

PETER J. MYER, OF DAYTON, OHIO.

SHOE-CREASER.

SPECIFICATION forming part of Letters Patent No. 745,228, dated November 24, 1903.

Application filed September 25, 1903. Serial No. 174,579. (No model.)

To all whom it may concern:

Be it known that I, PETER J. MYER, a citizen of the United States, residing at Dayton, in the county of Montgomery and State of Ohio, have invented certain new and useful Improvements in Shoe-Creaser; and I do declare the following to be a full, clear, and exact description of the invention, such as will enable others skilled in the art to which it applies to make and use the same, reference being had to the accompanying drawings, and to the figures of reference marked thereon, which form a part of this specification.

This invention relates to a hand-operative device for creasing the vamps of shoes for window display or for general use; and it consists of the novel features hereinafter described and claimed.

Preceding a detailed description of the invention, reference is made to the accompanying drawings, of which—

Figure 1 is a side elevation of the stationary part of the device in position. Fig. 2 is a top plan view of the last or creasing-form. Fig. 3 is a lower plan view of the last or creasing-form. Fig. 4 is a sectional view on the dotted line *a a* of Fig. 3. Figs. 5 and 6 are separate views of the creaser.

In a detailed description of my invention similar reference characters indicate corresponding parts.

The device now to be described is intended principally for shoe-dealers—that is to say, retail dealers—who are required to crease shoes for the general trade and for window display and the object of the creases being to enhance the appearance of the shoe.

The object of the invention is to provide a creasing device of a utility which adapts it for general use to crease shoes for window display and for other uses.

In a detailed description, 1 designates an arm detachably secured to a slotted plate 2 by a dovetail connection in a well-known manner, the two parts 1 and 2 constituting a bracket, which is designed to be secured to a wall or other place of support. The outer ex-

tremity 3 of the arm 1 terminates in a dovetail tenon, which is adapted to enter a corresponding dovetail recess 4 in the under side 50 of the last or form 5 and be secured therein by means of a thumb-screw 6. The form 5 is given the necessary shape to readily enter the shoe, and the upper surface thereof is provided with a series of corrugations or creases 55 7, which are embossed in the vamp of the shoe. As before stated, the form 5 is secured to the arm 1 by means of a thumb-screw. This enables one form to be displaced for another of larger or smaller dimensions whenever required. The creaser, which is operated by hand in connection with the form 5, is illustrated in Figs. 5 and 6 and consists of three or more parallel curved bars 8, with intervening spaces 9 for the reception of the crimps 60 or corrugations 7 on the shoe-form 5. The said bars terminate in handles 10 and have a curvature substantially as shown in Fig. 6, which conforms a cross-section of the last or form. 70

The device is operated as follows: For window display it is preferable to heat the form 5; but in other cases the creasing may be done without heat. The desired size of last or form being placed in suitable position on the bracket-arm, the shoe is placed in position thereon with the vamp directly over the corrugations. The creaser is then placed on top of the vamp, and suitable pressure is applied to said creaser by the hands or otherwise to 80 press the leather down into the crevices or grooves of the form. This being done, the creaser is given the necessary movement by means of the handles to press one side of the vamp and then the other, and the shoe moves 85 with the creaser in such movements of the latter, it requiring but a few such movements of the creaser to form the necessary creases in the vamp. It will be understood that the shoe and the creaser move together over the 90 corrugated surface of form 5.

Having described my invention, I claim—

A device for creasing shoes, consisting of a bracket-arm, a shoe-form detachably support-

ed on said arm and having its upper side provided with a series of corrugations, in combination with a coacting creasing member consisting of a series of parallel bars of uniform 5 curvatures conforming to a cross-section of the shoe-form, and terminating in end handles whereby said creasing member is adapted to be given reciprocating movement in di-

rections transverse of the shoe and to impart such movements to the shoe. 10

In testimony whereof I affix my signature in presence of two witnesses.

PETER J. MYER.
